HAT BLOCK

Sumner C. Cox, Fremont, and Bernard V. Everds,
Sandusky, Ohio

Application September 23, 1947, Serial No. 775,688

2 Claims. (Cl. 223—24)

1.

Our invention relates to a hat block and relates more particularly to a hat block of the type used in cleaning hats.

It is an object of our invention to provide an improved inflatable hat block which is adjustable for various head sizes.

It is a further object of our invention to provide an improved hat block which will be adjustable laterally but not vertically whereby various head sizes may be accommodated on the block, the upper portion of the block having a predetermined definite height.

Another object of our invention is to provide an improved hat block which will eliminate the necessity for removing the sweat band of a hat in order to secure a tight fit for such hat on the hat block.

A still further object of our invention is to provide an improved hat block which will be simple to manufacture, and yet be inexpensive and efficient in use.

Further objects of our invention and the invention itself will become more readily apparent from a purview of the following description, in which description reference will be had to the appended drawings, wherein:

Fig. 1 is a perspective view of the improved hat block of our invention;

Fig. 2 is a cross sectional view of the hat block of Fig. 1 taken on the line 2—2 of Fig. 1, showing in dotted lines an expanded size of said block; and

Fig. 3 is an enlarged cross sectional view taken on the line 3—3 of Fig. 2 of a portion of the top of said block.

The improved hat block 10 of our invention is preferably constructed of semi-hard heat-resistant rubber which when expanded, as is later herein specifically described, will allow a sufficiently hard outer surface for luring and polishing. It is preferably provided with a body 11 which is generally cone-shaped with a slightly convex head 12, and elongated slightly curved sides 13 having inturned ends 14 and 15 to which a hard rubber inner spindle receiving socket 16 is secured, as by vulcanization or the like. The socket 16 is provided with a central core portion 17, having a spindle receiving recess 18 therein, and an outwardly and downwardly extending inner cone 19 providing flat peripheral edge portions 20 for the block.

The socket 16 is preferably approximately one-half the height of the block itself and is of considerably harder rubber than the block. The inner lower sides of the block are preferably re-

inforced with metal and fabric or like stays 21 interposed between the portions 20 of the socket 16 and the sides 13 of the block, the stays 21 abutting and being secured to the lower inner portions of the said sides 13.

The upper head portion 12 of the block is preferably provided with substantially slightly convex metal stay strip 22 and fabric stay strip 23 integrally secured together and to the head 12 to assist in maintaining a uniform height of block and a smooth head surface therefor.

An air intake valve 24 of the usual type, such as that used with an automobile tire, is provided, adapted to be projected into and to communicate with the open area 25 of the block, whereby air or steam may be pumped into the block whereby the body of the block may be inflated by the air and accordingly, as the sliding band marker 26 may be adjusted, air is admitted until the block attains the proper size. The hat to be cleaned, polished, etc., is placed over the block when the same is deflated and a tight fit is thus secured therewith when the proper amount of air is admitted within the block.

25 It will be noted that the valve 24 may be used to act as a safety valve so that over-inflation may be avoided. Further, it should be observed that the metal and fabric stays are so arranged that pressure is applied horizontally to each of the several stays used and equally at all points in the hat block and flange, thereby eliminating any soft spots or openings which would cause "blistering" of the hat material.

To deflate, the stem of the valve is pressed 30 inwardly to permit air to escape from the block so that the crown of the hat can easily be removed therefrom.

It will be obvious that various departures may be made from the embodiment of our invention 35 herein illustrated and described without however departing from the spirit of our invention and the scope of the appended claims.

We claim:

40 1. A hat block comprising a substantially hollow body having an arched head portion and substantially straight side walls, an inner spindle receiving socket of substantially inverted W-shape in cross section secured to the downwardly extending ends of said side walls, said socket being spaced from the upper arched portion of the hat block body, the inner lower sides of the hat block wall being provided with reinforcement means integrally secured thereto, reinforcement means being disposed within the upper arched head portion and integrally secured

thereto, means for admitting a predetermined amount of air into that portion of the body disposed between said socket member and the inner surfaces of said body to expand said body in a horizontal direction to any desired size, the reinforcement means in said arched head portion preventing vertical expansion of said head portion.

2. A hat block comprising a substantially hollow body of semi-hard, heat-resistant rubber having an arched head portion and substantially straight side walls, a hard rubber inner spindle receiving socket of substantially inverted W-shape in cross section secured to the downwardly extending ends of said side walls, said socket being spaced from the upper arched portion of the hat block body, the inner lower sides of the hat block wall being provided with reinforcement means integrally secured thereto, reinforcement means being disposed within the upper arched head portion and integrally secured thereto,

10

5

means for admitting a predetermined amount of air into that portion of the body disposed between said socket member and the inner surfaces of said body to expand said body in a horizontal direction, the reinforcement means in said arched head portion preventing vertical expansion of said head portion.
